CORE TAKING APPARATUS

Edward Fay Brady, Long Beach, Calif., assignor
to Eastman Oil Well Survey Company, Denver,
Colo., a corporation of Delaware

Application May 13, 1948, Serial No. 26,785

5 Claims. (Cl. 255—72)

1

This invention relates to new and useful improvements in core taking apparatus and particularly to an improved core-receiving assembly for use with such apparatus.

In the drilling of petroleum wells, it is general and well known practice to cut or "take" a core or sample of the sub-surface formation or strata during the actual drilling operation by means of a coring apparatus which includes a core drill. The ordinary core drill is provided with a central bore and the core passes upwardly through said bore into a core-receiving assembly which retains said core therein. When brought to the surface the core is removed from the core-receiving assembly and may be examined to determine the dip and strike of the underground strata. It is, of course, essential that the core-receiving assembly effectively retain the entire core so that it may be fully recovered for subsequent examination; also, it is desirable that the core be marked in some manner so that it may be properly oriented to provide accurate information regarding the sub-surface structure.

It is one object of the present invention to provide an improved core-receiving assembly which is so constructed that the core being cut or taken will readily pass upwardly thereinto and which has means for properly marking or scribing said core for orientation purposes.

An important object of the invention is to provide an improved core-receiving assembly which will effectively retain a relatively soft core and which will just as readily retain a relatively hard core, whereby it may be efficiently employed in coring operation in all types of formations.

Still another object of the invention is to provide a core-receiving assembly having improved means for engaging and retaining a core of the sub-surface strata or formation which means also functions to efficiently "break off" or detach said core when the assembly is removed from the well to bring the core or sample to the surface for visual examination.

A still further object of the invention is to provide an improved core-receiving tube having flexible, retaining elements secured thereto and depending therefrom, and so arranged that the core or sample which is "cut" or taken during the coring operation, passes upwardly therebetween; said retaining elements being adapted to co-act with the usual core drill, whereby said elements are moved radially inwardly into engagement with the core, whereby said elements function to assure clean breaking off or detaching of said core and a subsequent retention thereof

2

within the core-receiving tube, the arrangement being particularly useful in the taking of cores in relatively hard formations.

The construction designed to carry out the invention will be hereinafter described together with other features of the invention.

The invention will be more readily understood from a reading of the following specification and by reference to the accompanying drawing, 10 wherein an example of the invention is shown, and wherein:

Figure 1 is a view partly in section and partly in elevation showing the improved apparatus mounted within a drill string,

15 Figure 2 is a partial isometric view of the improved core-receiving tube,

Figure 3 is a partial isometric view of the lower portion of the tubular section which connects the core-receiving tube with the remainder of 20 the apparatus,

Figure 4 is an enlarged, transverse, sectional view of the core-receiving assembly illustrating the same in position during the cutting of a core,

25 Figure 5 is a similar view illustrating the co-action between the retaining elements of the assembly with the core bit to illustrate the breaking off or detachment of a core from the formation, and

Figure 6 is a horizontal, cross-sectional view 30 taken on the line 6—6 of Figure 4.

In the drawings, the numeral 10 designates a drill pipe or string which extends axially through the well bore (not shown). A drill bit 11 of any desired construction is connected to the lower 35 end of the drill pipe or string and the body of said bit is substantially hollow with an axial opening 12 in its lower portion. The bit is provided with the usual cutting blades 13 and circulation ports 14.

40 The present invention resides in the core-receiving tube assembly which is generally indicated at A and said assembly is illustrated as combined with the removable core-taking apparatus described in the application of Charles T. Engle, Serial No. 631,052, filed November 27, 1945, now Patent No. 2,489,566. However, it is noted that the improved core-receiving assembly A may be employed with any standard core-taking equipment.

45 As illustrated, the assembly A has its upper end connected through a coupling 15 with a tubular barrel 16 within which a survey instrument S is mounted. The barrel 16 and core-receiving assembly A are disposed axially within an elongate tubular casing or housing 17, the upper end

of which is provided with a retractable latch mechanism 18, whereby the housing 17 may be rotatably connected to the drill pipe 10. A spear head 19 which is adapted to be engaged by a suitable fishing tool (not shown) carried by a wire line or cable is associated with the latch mechanism 18 and permits the casing 17 to be lowered and retracted from the drill stem by means of such wire line or cable. The barrel 16 which houses the instrument and the improved core-receiving assembly A are rotatably mounted with respect to the tubular casing or housing 17 by a suitable bearing 20.

The removable casing or housing 17 within which the core-receiving assembly A is mounted has a core bit 21 secured to its lower end and when the casing is in latched position within the drill stem 10, an external annular shoulder 22 on the core bit body engages or rests upon an annular seat 12a provided within the drill bit 11. This permits the lower portion of the core bit to extend outwardly through the bore 12a in the drill bit and the extreme lower end of the core bit is formed with suitable cutting teeth 23. The core bit is provided with an axial bore 24 extending entirely therethrough and the intermediate portion of said bore is generally inclined or tapered outwardly as indicated at 25. Suitable circulation ports 26a extend through the wall of the core bit.

It will be evident that with the casing 17 rotatably latched in position within the drill pipe 10, a rotation of said pipe will impart rotation to the drill bit and also to the core bit. As drilling proceeds, a core is cut by the bit 21 and passes upwardly into the bore 24 thereof. The improved core-receiving assembly A has its lower portion projecting downwardly into the bore of the core bit and thus the core entering said bore passes upwardly into the assembly A. Because of the rotatable bearing connection 20 between the instrument barrel 16 and the housing or casing 17, it will be obvious that the core-receiving assembly A may remain stationary, while the casing 17 and the drill pipe 10 are rotated during the cutting operation.

The improved core-receiving assembly A is clearly shown in Figures 2 to 6 and this assembly includes a core-receiving tube 26 which has a substantially straight bore 26b extending entirely therethrough. A plurality of core-retaining elements 27 in the form of flat spring bars have their upper ends suitably secured within the lower portion of the bore. The elements 27 are spaced equi-distant around tube 26 and may vary in number, with four being illustrated. Each element or bar is provided with a pair of inwardly directed sharpened dogs 28 at its lower end. An inwardly curved resilient spring member or finger 29 has its lower portion fastened to each retaining element and will function, as will be explained, to retain cores of softer formation. Since the members 29 are secured to the inner faces of the retaining elements 27, said members are spaced equi-distant radially from each other and as is clearly shown in Figure 4, the upper ends of the members or fingers 29 project inwardly into the path of the core entering the tube 26.

For marking a core which enters the bore 26b of the tube 26 an elongate vertical scribe or bar 30 is suitably mounted within a radial slot 31 formed in the wall of the tube. This scribe may have its inner surface formed with teeth or serrations to assure effective marking of cores of harder formations.

The upper end of the bore of the tube is enlarged slightly as indicated at 26c and this portion of said tube has a telescoping or slip fit over the lower end of an upper tubular section 33. The upper end of the section 33 is connected through the coupling 15 with the barrel 16 which houses the survey instrument. The scribe or marking bar 30 mounted within the tube 26 has its upper end adapted to engage within a slot 35 which is formed in the lower portion of the tubular section 33 when the tube telescopes said section. It is noted that the telescoping or slip fit between the tube 26 and the section 33 is a relatively tight friction fit.

In the operation of the apparatus, the improved core-receiving assembly A is connected to the barrel 16 through the coupling 15. The core-receiving tube 26 is engaged with the lower end of the tubular section 33 through the telescoping or slip joint and this connection causes the upper end of the marking bar or element 30 to engage within the slot 35 in section 33. The assembly is then mounted within the outer tubular casing or housing 17 which has the core bit 21 threaded onto its lower end. With the assembly disposed in position within the casing or housing 17, the lower ends of the retaining elements or bars 27 which depend from the core-receiving tube 26 engage the inclined portion 25 of the bore of the core bit 21. This position of the bits is illustrated in Figures 1 and 4. The tubular casing 17 is coupled through the latching mechanism 18 with the drill stem 10 and at this time the core bit 21 projects through the bore 12 of the drill bit 11, as is clearly shown in Figure 1.

The drilling operation is then carried out by imparting rotation to the drill pipe or stem 10 and such rotation is transmitted through the latch mechanism 18 and tubular casing 17 to the core bit 21, whereby a core of the formation is cut by said core bit. This core passes upwardly through the bore of the core bit and past the retaining elements 27 and spring fingers 29 into the interior or bore 26b of the tube 26. As the core passes upwardly into the core-receiving tube 26 and its connected tubular section 33, the scribe or marking bar 30 functions to clearly mark said core. If the core is one of a softer formation, the resilient curved fingers 29 which are secured to the inner surfaces of the retaining elements 27 engage said core and function to retain it within the core-receiving tube. It is noted that the spring fingers 29 have a greater resiliency or flexibility than the retaining elements 27, the latter having a certain degree of resiliency but actually being stiffer than the fingers 29.

If a harder formation is being drilled, the core of such harder formation passes upwardly through the core bit in the same manner and functions to spread or flatten the spring fingers 29, passing by said fingers into the bore of the tube. As this harder core moves into the core-receiving tube 26, the scribe or marking bar 30 efficiently marks said core. The sharpened dogs 28 on the lower ends of the retaining elements or bars 27 engage the outer surface of this harder core to retain the same.

Experience has shown that in many cases it is difficult to obtain a sharp breaking off of the core which has entered the tube and this is particularly true when the core is of a harder formation. The particular apparatus disclosed makes it possible to detach or break off the core

when it is desired to retrieve the same. The connection between the assembly A and its connected barrel 16 with the tubular casing or housing 17 is such that not only can the casing rotate with respect to the assembly and barrel 16 but also, the casing may undergo a limited longitudinal movement with respect to said barrel and said assembly. This is possible because the connecting pin 20a above the bearing 20 is shorter than the recess 20b in the casing 17. Thus, when it is desired to retrieve the core, a suitable fishing tool is engaged with the spear head 19 and an upward pull is exerted upon the spear. Such upward pull first releases the latching mechanism 18 and then imparts an upward movement to the casing 17 and the core bit 21. Since the core is still attached to the formation at this time and since it is in frictional engagement with the retaining bars 27, the tube 26 and its connected parts are held stationary by such frictional engagement. Therefore, the upward pull on the casing 17 and the core bit 21 causes said bit to move upwardly with respect to the retaining elements or bars 27 of the core-receiving tube 26. This relative upward movement causes the inclined portion 25 of the bore of the core bit to co-act with the flexible retaining elements or bars 27 to move said elements or bars radially inwardly. Such inward movement of the bars 27 forces the sharpened dogs 28 firmly into the core which is disposed therebetween and will result in a sufficient scoring of the core to assure breaking off at this point. Continued upward movement will then retrieve the core with the entire assembly.

From the foregoing it will be seen that a simple core-receiving assembly is provided. It is possible to receive and retain the softer formation cores by means of the curved spring fingers 29, while the harder cores are detached and retained by the flexible retaining elements 27. In either case the core which enters the tube 26 is accurately marked by the scribe or marking bar 30. It will be evident that the arrangement permits a coaction between the bore of the core bit with the retaining elements to urge said element inwardly into firm engagement with the core disposed therebetween. It is noted that although the arrangement whereby the elements 27 may be moved inwardly is especially advantageous in assuring proper breaking off of the harder cores, the inward movement of the retaining elements is also desirable in urging the resilient fingers 29 into firmer engagement with the softer formation cores. The provision of the slip or telescoping joint between the tube 26 and its associated tubular section 33 makes it possible to easily remove the core which has been obtained after the apparatus is brought to the surface. As has been noted, it is desirable that the spring fingers 29 have greater flexibility than the retaining elements or bars 27; however, the latter have sufficient inherent resiliency to assure their engagement with the core disposed therebetween at all times. It is again noted that although the improved core-receiving assembly has been shown with a particular type of core-taking apparatus, it may be employed with any of the well known core-taking equipment now in general use.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A core-receiving assembly for core-taking apparatus including, a core-receiving tube, a plurality of retaining elements mounted on the lower end of said tube and depending in a plane therbelow, said elements being constructed of metallic bars having an inherent resiliency urging them radially inwardly, sharpened dogs mounted on the extreme lower end of each element, a flexible spring finger secured to the inner surface of each element intermediate its ends, and an elongate scribe mounted in the wall of the tube between two of the elements and having a toothed edge of considerable length extending radially inwardly into the bore.

2. A core-receiving assembly for use with a core-taking apparatus including, an elongate core-receiving tube, an associated tubular section having its lower end telescoping the upper end of the tube and frictionally engaged therewith, a scribe bar secured in the wall of said tube and directed radially inwardly into the bore thereof, said bar extending throughout the length of said tube and having its extremities projecting beyond the upper and lower ends thereof, the tubular section having a slot therein for receiving the upper projecting end of the bar when said section is connected with the tube, and a plurality of flexible retaining elements secured to the lower end of the tube and depending therefrom said elements being spaced at various radial points around said tube.

3. The combination with a core bit having a tapered axially extending bore, of a core receiving assembly including, a core receiving tube of considerable length to receive the core to be cut and mounted so as to be axially aligned with the bore of said bit and to permit limited relative movement between it and the bit, a plurality of retaining elements secured to the tube and extending downwardly into the tapered bore of the core bit, whereby a core cut by said bit and passing upwardly through the bore thereof and into the core receiving tube passes between the retaining elements and is engaged thereby, said elements contacting the tapered bore of said core bit and co-acting therewith upon a movement of the core bit relative to the elements and the tube, whereby said elements are moved radially inwardly, means on the extreme lower ends of said retaining elements for engaging and effectively retaining a core of hard formations, and an elongate radially directed scribing means mounted in the wall of the core receiving tube and having a series of teeth on its inner edge projecting into the tube for marking the core entering said tube, said scribe being positioned between the retaining elements and of such length as to extend to a point beyond the upper ends thereof.

4. The combination with a core bit having a tapered axially extending bore, of a core receiving assembly including a core receiving tube of considerable length to receive the core to be cut and mounted so as to be axially aligned with the bore of said bit and to permit limited relative movement between it and the bit, a plurality of retaining elements secured to the tube and extending downwardly into the tapered bore of the core bit, whereby a core cut by said bit and passing upwardly through the bore thereof and into the core receiving tube passes between the retaining elements and is engaged thereby, said elements contacting the tapered bore of said core

bit and co-acting therewith upon a movement of the core bit relative to the elements and the tube, whereby said elements are moved radially inwardly, means on the extreme lower ends of said retaining elements for engaging and effectively retaining a core of soft formation, and an elongate radially directed scribing means mounted in the wall of the core receiving tube and having teeth on its inner edge which project into the tube for marking the core entering said tube, said scribe being positioned between two retaining elements and extending to a point beyond the upper ends thereof.

5. In well bore core taking apparatus for use with a drill pipe having a drill bit with an axially extending bore having a shoulder therein, a tubular member provided with a core bit having an axially extending bore and an external shoulder above the core bit for engaging the shoulder in the drill bit bore, said tubular member and core bit being receivable in and removable from the drill stem without removing the drill pipe and drill bit from the well bore, means for connecting the tubular member to the drill pipe for rotation therewith and when so connected said core bit will extend through the drill bit, a core receiving barrel of considerable length in the tubular member for receiving the entire core to be

10 cut, said barrel being so mounted that limited relative axial movement is present between it and the tubular member, a plurality of resilient core retaining elements carried by and extending downwardly from the lower end of the core barrel, and cooperating means between the retaining elements and the core bit for positively flexing the elements inwardly to engage a core upon relative axial movement between the core barrel and the core bit.

15 EDWARD FAY BRADY.
